Primary Examiner—Nelson C. Holtje*Attorney, Agent, or Firm*—Townsend and Townsend and Crew, LLP[57] **CLAIM**

The ornamental design for a timer, as shown and described.

DESCRIPTION

FIG. 1 is a perspective view of a timer showing my new design;

FIG. 2 is a top plan view thereof;

FIG. 3 is a front elevational view thereof;

FIG. 4 is a left side elevational view thereof;

FIG. 5 is a right side elevational view;

FIG. 6 is a rear elevational view thereof;

FIG. 7 is a bottom plan view thereof; and,

FIG. 8 is a front elevational view of a second embodiment of my new design of FIGS. 1-7 wherein the only difference is the circular readout window.
